MEMORY UNIT FOR AUTOMATIC SHUTTLE CHANGING ON LOOMS HAVING A PLURALITY OF SHUTTLES

Emile Achille Butin, Lyon, France

Application April 8, 1953, Serial No. 347,493

Claims priority, application France April 18, 1952

7 Claims. (Cl. 139—232)

My invention has for its object improvements in the automatic shuttle-changing in looms operating with a number, say four, of wefts and shuttles, said change of shuttle being operated in a purely mechanical manner without stopping the operation of the loom.

According to my invention, two control means are provided which are operated respectively through the weft feeler and through the shuttle box selector arrangement, the former setting the shuttle-changing mechanism for operation, the actual change being produced immediately if the shuttle box corresponding to the color or nature of the shuttle, the supply of which is exhausted, is still in the operative position, or being produced only when this shuttle box returns to the operative position if a shuttle box change has occurred meanwhile. To this end, a recording system which I will term a memory unit is inserted between the weft feeler and the arrangement providing for the substitution of a replenished shuttle for the empty shuttle.

In accompanying drawings illustrating a preferred embodiment of my invention:

Fig. 1 is a front elevational view of the memory unit and associated parts.

Figs. 2, 3 and 4 are side views thereof at different stages of operation.

The actual so-called memory unit which forms the object of my invention includes, in the case illustrated of a loom provided with four shuttles corresponding to four types of weft, the following members:

A barrel 27 is revolvably mounted round its spindle 100 in a carrier frame 29. The said barrel is rigid with an arm 33 connected through a rod 101 with the means controlling the shuttle-box arrangement, i. e. with the means providing for the change of weft when required; this control system 102 is adapted to move upwardly and downwardly so as to produce through the above-mentioned transmission members 33 and 101, a partial revolution of the barrel 27 round its spindle 100 either in one direction or in the other.

To the periphery of the barrel are secured four keys or projections 32 distributed angularly in the plane of the drawing and also perpendicularly with reference to said plane. These keys 32 are thus located on a helical line drawn on the barrel 27.

The frame 29 carrying the said barrel is suspended to a stationary shaft 31 round which it may rock so as to produce simultaneously a shifting of the barrel 27. The frame 29 is urged back by a spring 103 against a stationary adjustable stop 104 which defines its inoperative position. To this frame is secured a cable 11 which allows producing its pivotal movement round the spindle 31.

To a stationary spindle 44 are suspended levers 37 the number of which is four in the case considered of a four-pick loom. Only one of the said levers is illustrated in Figs. 2 to 4. These levers are referred to hereinafter as recording levers and are provided each with a notch 46 and a hook-shaped extension 45 projecting over and partly

encircling the barrel 27 and the end of which registers with the corresponding key 32 carried by the said barrel 27.

Further levers 38, also four in number, are positioned in register with the corresponding levers 37 and are also freely suspended to a stationary shaft 55. These levers 38 are designated hereinafter as covering levers and they include each a crescent-shaped section 105 and a tail-piece 106 normally engaged by the notch of the corresponding lever 37.

10 To the shaft 55 is also pivotally secured a further series of so-called control levers 39. Each of the said levers 39 corresponds to one of the above mentioned covering levers 38 and includes underneath the latter an extension 56 serving as a bearing. The control levers 39 include, furthermore, beyond their common pivot constituted by the shaft 55, a counterweight 107 which makes the corresponding lever tip over and urges it, when inoperative, against a stationary bar 108. Underneath the levers 38 is provided a chain constituted by selecting plates 35, the 15 said chain being controlled in the usual manner by the shuttle-box mechanism of the loom. These plates extend throughout the length occupied by the four juxtaposed levers 39 and they are provided with suitably located bosses 36.

20 Further levers 43 inserted between the successive levers 38 are freely and pivotally secured to the stationary spindle 49. These levers will be termed hereinafter "the release levers" and they include each a sector-shaped part provided with a notch 48, the said notch being located nearer the 25 shaft 49 than the periphery of the crescent-shaped part 105 of any lever 38. In other words, the notches 48 in the levers 43 are located at a level which is lower than that of the crescent-shaped parts 105 of the levers 38. The release levers 43 are provided with extensions 109 to the 30 ends of which are attached cables 6, 7, 8, 9, respectively.

To the spindle 49 is pivotally secured, to the rear of the levers 43, a further lever 52. This lever is provided at one end with a transverse bar 53 extending throughout the breadth occupied by the extensions 109 of the levers 43 and at the other end with an extension 110 carrying in its turn a small transverse bar 54 extending throughout the breadth occupied by the tail pieces 106 forming part of the levers 38, but at a level lower than that of the bearing extensions 56 of the levers 39. This lever 52 will be termed hereinafter "the general release lever." To the upper end of the said lever 52 is attached a cable 12.

Lastly, the above-mentioned spindle 49 carries a frame 41 the outer end of which carries a spindle 50 to which are pivotally secured four catches 42. Each of the said 50 catches extends partly over the section 105 of the corresponding lever 38 and over the notch 48 in the adjacent corresponding lever 43. The frame 41 is rigid with a projection 51 engaging a cam 28 driven into a continuous rotary movement round its axis 111 by a chain 34 which 55 is driven in its turn by the crankshaft of the loom.

The memory unit described hereinabove is secured to one of the sides of the frame of the weaving loom (Fig. 1) through the supports 4 and the rod 5.

To the other side of the loom is secured the shuttle holder 2 which, in the case considered of a loom operating with four different types of weft, includes four channels in which are housed the spare shuttles. The weft feeler 3 is also located on the same side as the shuttle holder 2.

The cables 6, 7, 8, 9, respectively secured to the ends 65 109 of the levers 43 are sheathed together inside a tube 13 and extend therewith throughout the breadth of the loom. This tube 13 is carried by supports 14. The cables 6, 7, 8 and 9 pass through a small plate 15 secured to the frame of the shuttle holder 2 and they are connected respectively with the members cooperating with the four channels of the shuttle holder which control the re-

lease of a full shuttle to provide for its operation, as fully disclosed in my prior U. S. Patents Nos. 2,493,570 and 2,572,107. These cables, starting from the memory unit, pass also through the tensioning means 16 (Fig. 2). As to the cable 11 attached to the frame 29 carrying the barrel 27 and to the cable 12 attached to the end of the lever 52, they also pass inside the tube 13 across a portion of the breadth of the loom, after which they enter a branch tube 19 and end in register with the feeler 3 adapted to check in the usual manner the amount of weft carried by the shuttle during operation each time said shuttle registers with said feeler.

In Fig. 1, 17 designates the lever of the feeler, which is actuated by said feeler each time the provision of weft remaining in an operative shuttle is about to be exhausted. Said lever 17 is connected through a rod 25 with a lever 21 adapted to rock round a spindle 23 carried inside a bearing 112 at the lower end of the loom. To said lever 21 is attached the end of the cable 11.

A lever 18 is adapted when engaged to produce the engagement of the different parts which set the double box on the batten shaft in a position such that it may receive a replenished shuttle and release the preceding operative empty shuttle, said arrangement being of the type fully disclosed in my prior above-mentioned specifications. Said lever 18 is connected through a rod 26 with a lever 22 carried by the above-mentioned spindle 23. Said lever 22 is connected in its turn with the above-referred cable 12.

It should be remarked that the lever 21 is revolubly carried by the spindle 23 while the lever 22 is keyed to said spindle. The latter is also rigid with a lever 24 controlling the transportation of a replenished shuttle between the storing holder therefor and the opening box on the batten, after said replenished shuttle has been released from its storing holder, as disclosed in my prior specification 2,572,107 and my copending application Ser. No. 347,495, filed on April 8, 1953.

Before describing the general operation of said system, it should be remembered that the actual memory unit is connected on one hand with the shuttle-box control system of the loom which produces the reciprocating rising and lowering movement of the member 102 in the direction of the arrows 120 and the progression of the chain of small selecting plates 35, said memory unit being connected on the other hand with the crankshaft of the loom which produces the rotation of the cam 28.

Consequently: the barrel 27 assumes permanently a partial rotary movement alternatingly in clockwise and anti-clockwise direction, as shown by the arrows 121; the chain of plates 35 progresses continuously in the direction of the arrow 122; and the frame 41 assumes permanently a reciprocating oscillatory movement in the direction of the arrow 123 round the shaft 49 and carries along with it during its movement the catches 42 mounted on said frame.

The three abovementioned movements are without any effect on the normal operation of the loom if the feeler has not detected an exhaust of the weft thread in a shuttle to such an extent that the replacement of the latter has become necessary.

As a matter of fact, the catches 42 are raised by the crescent-shaped part 105 of the lever 38 so as to be out of reach of the notches 48 in the levers 43 over which said catches move without being capable of engaging the latter (see Fig. 2).

When the feeler 3 is operative as a consequence of a shuttle being exhausted, said feeler draws the rocking frame 29 through the agency of the lever 17, of the rod 25, of the lever 21 and of the cable 11 and shifts it in the direction of the arrow 124.

At the moment of the operation of the feeler, the movement of the shuttle-box control means has shifted the barrel 27 into a position such that the key 32 correspond-

ing to the operative weft lies in front of the crook-shaped end 45 of the corresponding recording lever 37.

The frame 29 and the barrel 27 being drawn by the cable 11 and being shifted thereby in the direction of the arrow 124, one of the abovementioned keys of the barrel produces a clockwise rocking of a recording lever 37 round its axis 44. Said lever allows then the covering lever 38 to drop under the action of gravity, the end 106 of last mentioned lever being released with reference to the notch 46 in the lever 37.

Two possibilities may then arise, for when the shuttle in use at that time has been sensed and found to be near exhaustion, it must still perform one complete to-and-fro movement through the shed, penetrating once into the shuttle box on the opposite side of the loom, before returning to the box in which it will be withdrawn from use and replaced by another shuttle.

It may happen, for example, either that the box into which the empty shuttle penetrates remains in use, in which first case the shuttle returns immediately and is replaced, or that this same box is changed at the very moment when the empty shuttle penetrates, so that another box and another shuttle come into use, and in this second case the empty shuttle will not have returned to the box in which it is to be withdrawn from use and replaced by a full shuttle, and it is the purpose of the present invention to provide for such return and replacement when, and not until, the box into which the empty shuttle penetrates comes back into use.

30 In the first case the boss 36 of the shuttle in use remains in position under the lever 39, which lever is in the position shown in Figure 4, its end 56 being lowered and allowing the lever 38, released from the notch 46, to rock sufficiently for the crescent-shaped section 105 to uncover the notch 48 of the corresponding lever 43.

The corresponding catch 42 carried by the frame 41 engages then the notch 48 during the rocking movement of said frame towards the right hand side. This rocking of the frame towards the right hand side provides thus a rocking in the same direction, through the catch 42, of the release lever 43. The latter exerts through its extension 109 a tensioning action on the cable 6, 7, 8 or 9, which produces on the other side of the loom the release in the shuttle holder 2 of a shuttle similar to that which is to be changed.

During this movement, the extension 109 of the release lever 43 also exerts a thrust on the small bar 53 on the lever 52 and shifts the latter along with it. The lever 52 releases through its cable 12 the means urging the shuttle downwardly by engaging the shuttle-changing mechanism through the lever 22 which, on one hand, controls the lever 18 and, on the other hand, the lever 24 through the shaft 23.

It should be remarked also that the above-mentioned general release lever 52 allows the lever 37 to be reset whereby the different levers are returned into their starting position illustrated in Fig. 2. For this purpose, the lever 52 acts through the transverse rod 54 rigid with its extension 110 on the lever 38 so that after each shuttle-changing operation, all the parts return automatically into their normal position inside the memory unit and the latter is immediately ready for further operation.

In the second case, where a change of box intervenes in the shuttle-change cycle, the boss 36 raising the lever 39 advances and this lever is lowered again by its counter-weight 107 against the bar 108. In this position the released lever 38 is arrested in its rocking movement by the extension 56 of the lever 39 serving as a bearing. As seen in Figure 3, rocking of the lever 38 is insufficient then for its crescent-shaped section 105 to uncover the notch 48 of the lever 43, so that nothing further happens in this cycle, the catch 42 being unable to penetrate into the notch 48 of the lever 43. The mechanism acts as a memory recording for future use the need of replacement of the empty shuttle to be carried out

later only when a further boss 36 appears under the same lever 39. This can occur only when the same shuttle box comes back into use and the lever 39, rising on the side of its counter-weight 107, lowers its bearing extension 56 to allow the lever 38 to fulfill its rocking movement and uncover the notch 48 of the lever 43.

I claim:

1. In the shuttle-changing system of a multiple-weft loom, the combination of a weft feeler, shuttle-changing mechanisms for the different wefts, shuttle-box selector, a shuttle-box mechanism controlling the latter and a memory unit comprising recording levers, the number of which is equal to that of the shuttles in the loom, a rotary barrel controlled by the shuttle-box mechanism and including a number of projections equal to that of the shuttles, a shiftable carrier for the barrel, means whereby the weft feeler upon engagement with an empty shuttle shifts transiently the shiftable carrier into a position for which the barrel projection corresponding to the empty shuttle meets the corresponding recording lever and shifts it into a predetermined angular position, release levers operatively connected with the corresponding shuttle-changing mechanisms and provided each with a notch, catches submitted to a continuous reciprocating movement and adapted to engage each the notch in a different release lever and to shift thereby said release lever into a position for which it controls the corresponding shuttle-changing mechanism, plural means engaging normally each one of the recording levers and released with reference thereto when the corresponding recording lever has been shifted into the above-mentioned predetermined position, said plural means being adapted to allow, only when fully released, the operative engagement of the corresponding catches in the notches of the corresponding release levers, control members holding the corresponding last mentioned means, when released, in an intermediate position and means whereby the shuttle-box selector transiently releases the corresponding holding members at the moment of operation of the corresponding shuttles and thereby releases the corresponding last mentioned means to allow the latter to enter its completely released position and to make the corresponding release lever become operative.

2. In a shuttle-changing system of the multiple-shuttle type, the combination of a weft feeler, a shuttle-box control mechanism, a shuttle-changing mechanism for different wefts, a shuttle box selector controlled by the shuttle-box control mechanism and a memory unit comprising recording levers, the number of which is equal to that of the shuttles in the loom, a rotary barrel controlled by the shuttle-box control mechanism and including a number of projections equal to that of the shuttles, a shiftable carrier for the barrel, means whereby the weft feeler upon engagement with an empty shuttle shifts transiently the shiftable carrier into a position for which the barrel projection corresponding to the empty shuttle meets the corresponding recording lever and shifts it into a predetermined angular position, release levers operatively connected with the corresponding shuttle-changing mechanisms and provided each with a notch, catches submitted to a continuous reciprocating movement and adapted to engage each the notch in a different release lever and to shift thereby said release lever into a position for which it controls the corresponding shuttle-changing mechanism, covering levers each normally engaged by the corresponding recording lever and released with reference thereto when the said corresponding recording lever has been shifted into the above-mentioned predetermined position, said covering levers normally covering the notches in the corresponding release levers and adapted when released to drop into a notch-uncovering position, control levers corresponding each to a shuttle and controlled selectively by the shuttle-box selector at the moment of the passage of the corresponding shuttle.

5 to enter an operative position, said control levers when inoperative preventing the corresponding covering levers from dropping into their notch-uncovering positions, the location of any control lever in its operative position allowing said dropping of the corresponding covering lever and thereby operation of the corresponding release lever and shuttle-changing mechanism.

10 3. In a shuttle-changing system of the multiple-shuttle type, the combination of a weft feeler, a shuttle-box control mechanism, a shuttle-changing mechanism for different wefts and including means operating to cause discharge of the empty shuttle and supply of a replenished shuttle, a shuttle box selector controlled by the shuttle-box control mechanism and a memory unit comprising recording levers, the number of which is equal to that of the shuttles in the loom, a rotary barrel controlled by the shuttle-box control mechanism and including a number of projections equal to that of the shuttles, a shiftable carrier for the barrel, means whereby the weft feeler upon engagement with an empty shuttle shifts transiently the shiftable carrier into a position for which the barrel projection corresponding to the empty shuttle meets the corresponding recording lever and shifts it into a predetermined angular position, release levers operatively connected with the corresponding shuttle-changing mechanisms and provided each with a notch, catches submitted to a continuous reciprocating movement and adapted to engage each the notch in a release lever and to shift thereby said release lever into a position for which it controls the corresponding shuttle-changing mechanism, covering levers each normally engaged by the corresponding recording lever and released with reference thereto when the said corresponding recording lever has been shifted into the above-mentioned predetermined position, said covering levers normally covering the notches in the corresponding release levers and adapted when released to drop into a notch-uncovering position, control levers corresponding each to a shuttle and controlled selectively by the shuttle-box selector at the moment of the passage of the corresponding shuttle to enter an operative position, said control levers when inoperative preventing the corresponding covering levers from dropping into their notch-uncovering positions, the location of any control lever in its operative position allowing said dropping of the corresponding covering lever and thereby operation of the corresponding release levers and shuttle-changing mechanism, a common release lever controlled through the operation of any of the first mentioned release levers and controlling the means operating the shuttle box to allow the change of the empty shuttle.

4. In the shuttle-changing system of a multiple-weft loom, the combination of a weft feeler, shuttle-changing mechanisms for the different wefts, a shuttle-box selector, a shuttle-box mechanism controlling the latter and a memory unit comprising recording levers, the number of which is equal to that of the shuttles in the loom, a rotary barrel controlled by the shuttle-box mechanism and including a number of projections equal to that of the shuttles, a shiftable carrier for the barrel, means whereby the weft feeler upon engagement with an empty shuttle shifts transiently the shiftable carrier into a position for which the barrel projection corresponding to the empty shuttle meets the corresponding recording lever and shifts it into a predetermined angular position, release levers operatively connected with the corresponding shuttle-changing mechanisms and provided each with a notch, catches submitted to a continuous reciprocating movement and adapted to engage each the notch in a different release lever and to shift thereby said release lever into a position for which it controls the corresponding shuttle-changing mechanism, plural means engaging normally each one of the recording levers and released with reference thereto when the corresponding recording lever has been shifted into the above-mentioned predetermined position, said plural means being adapted to allow, only

when fully released, the operative engagement of the corresponding catches in the notches of the corresponding release levers, control members holding the corresponding last-mentioned means, when released, in an intermediate position and means whereby the shuttle box selector transiently releases the corresponding holding members at the moment of operation of the corresponding shuttles and thereby releases the corresponding last mentioned means to allow the latter to enter its completely released position and to make the corresponding release lever become operative and means controlled by the release levers and adapted upon operation of any of the latter to return the released first mentioned means into engagement with the recording lever.

5. In a shuttle-changing system of the multiple-shuttle type, the combination of a weft feeler, a shuttle-box control mechanism, a shuttle-changing mechanism including means operating to cause discharge of the empty shuttle and supply of a replenished shuttle, a shuttle box selector controlled by the shuttle-box control mechanism and a memory unit comprising recording levers, the number of which is equal to that of the operative shuttles in the loom, a rotary barrel controlled by the shuttle-box control mechanism and including a number of projections equal to that of the shuttles and registering with the corresponding recording levers, a shiftable carrier for the barrel, means whereby the weft feeler upon engagement with an empty shuttle shifts transiently the shiftable carrier into a position for which the barrel projection corresponding to the empty shuttle meets the corresponding recording lever and shifts it into a predetermined angular position, release levers operatively connected with the corresponding shuttle-changing mechanisms and provided each with a notch, catches submitted to a continuous reciprocating movement and adapted to engage each the notch in a release lever and to shift thereby said release lever into a position for which it controls the corresponding shuttle-changing mechanism, covering levers each normally engaged by the corresponding recording lever and released with reference thereto when the said corresponding recording lever has been shifted into the above-mentioned predetermined position, said covering levers normally covering the notches in the corresponding release levers and adapted when released to drop into a notch-uncovering position, control levers corresponding each to a shuttle and controlled selectively by the shuttle-box selector at the moment of the passage of the corresponding shuttle to enter an operative position, said control levers when inoperative preventing the corresponding covering levers from dropping into their notch-uncovering positions, the location of any control lever in its operative position allowing said dropping of the corresponding covering lever and thereby operation of the corresponding release levers and shuttle-changing mechanism, a common release lever controlled through the operation of any of the first mentioned release levers and controlling the means operating to allow the change of the empty shuttle and means controlled by the general release lever and adapted upon operation of the latter to return the released covering lever into engagement with the corresponding recording lever.

6. In the shuttle-changing system for a loom, the provision of a weft feeler, a shuttle-changing mechanism for each of a plurality of different wefts, a shuttle-box control mechanism, said feeler and shuttle-changing mechanism being all positioned to one side of the loom, a shuttle-box selector controlled by the shuttle-box control mechanism and positioned on the other side of the loom and a memory unit positioned above said selector and comprising recording levers, the number of which is equal to that of the shuttles in the loom, a rotary barrel controlled by the shuttle-box control mechanism and including a number of projections equal to that of the shuttles, a shiftable carrier for the barrel, a cable wherethrough the weft feeler upon engagement with an empty shuttle

shifts transiently the shiftable carrier into a position for which the barrel projection corresponding to the empty shuttle meets the corresponding recording lever and shifts it into a predetermined angular position, release levers, cables operatively connecting the different release levers with the corresponding shuttle-changing mechanisms and provided each with a notch, catches submitted to a continuous reciprocating movement and adapted to engage each the notch in a different release lever and to shift thereby said release lever into a position for which it controls the corresponding shuttle-changing mechanism, plural means engaging normally each one of the recording levers and released with reference thereto when the corresponding recording lever has been shifted into the above-mentioned predetermined position, said plural means being adapted to allow, only when fully released, the operative engagement of the corresponding catches in the notches of the corresponding release levers, control members holding the corresponding last mentioned means, when released in an intermediate position, means whereby the shuttle-box selector transiently releases the corresponding holding members at the moment of operation of the corresponding shuttles and thereby releases the corresponding last mentioned means to allow the latter to enter its completely released position and to make the corresponding release lever become operative and a tube containing the different cables and extending across the loom.

7. In the shuttle-changing system for a loom, the provision of means operating to cause discharge of the empty shuttle and supply of a replenished shuttle, a weft feeler, a shuttle-changing mechanism for each of a plurality of different wefts, a shuttle-box control mechanism, said feeler and shuttle-changing mechanism being all positioned to one side of the loom, a shuttle-box selector controlled by the shuttle-box control mechanism and positioned on the other side of the loom and a memory unit positioned above said selector and comprising recording levers, the number of which is equal to that of the shuttles in the loom, a rotary barrel controlled by the shuttle-box control mechanism and including a number of projections equal to that of the shuttles, a shiftable carrier for the barrel, a cable wherethrough the weft feeler upon engagement with an empty shuttle shifts transiently the shiftable carrier into a position for which the barrel projection corresponding to the empty shuttle meets the corresponding recording lever and shifts it into a predetermined angular position, release levers, cables operatively connecting the different release levers with the corresponding shuttle-changing mechanisms and provided each with a notch, catches submitted to a continuous reciprocating movement and adapted to engage each the notch in a different release lever and to shift thereby said release lever into a position for which it controls the corresponding shuttle-changing mechanism, covering levers each normally engaged by the corresponding recording lever and released with reference thereto when the said corresponding recording lever has been shifted into the above-mentioned predetermined position, said covering levers normally covering the notches in the corresponding release levers and adapted when released to drop into a notch-uncovering position, control levers corresponding each to a shuttle and controlled selectively by the shuttle box selector at the moment of the passage of the corresponding shuttle to enter an operative position, said control levers when inoperative preventing the corresponding covering levers from dropping into their notch-uncovering positions, the location of any control lever in its operative position allowing said dropping of the corresponding covering lever and thereby operation of the corresponding release levers and shuttle-changing mechanism, a common release lever controlled through the operation of any of the first mentioned release levers and controlling the means operating to allow the change of the empty shuttle and means controlled by the general release lever and adapted upon operation of the latter to return the released covering lever into engagement with the corresponding recording lever.

the common release lever and means controlled by the general release lever and adapted upon operation of the latter to return the released covering lever into engagement with the corresponding recording lever.
